UNITED STATES PATENT OFFICE.

JOHN E. MILLER, OF VAN NUYS, CALIFORNIA.

CRANK-CASE COOLER FOR MOTOR VEHICLES.

Application filed September 1, 1922. Serial No. 385,680.

This invention relates to internal combustion engines and more particularly to means for cooling the crank case of internal combustion engines.

It is an object of the present invention to provide means for defining a circulation of air through the crank case of an internal combustion engine, and a further object is to provide means for admitting air and for preventing its return and to provide other means for permitting the escape of the admitted air from the crank case.

It is an object to provide air circulating means whereby cool air is constantly drawn into and discharged from the crank case of an internal combustion engine for cooling the crank case and operating parts and, therefore, for reducing the consumption of lubricating oil and also for reducing carbonaceous deposits resulting from the hardening of the oil substances in the hot portions of the motor.

Other objects will be made manifest in the following specification of an embodiment of the invention illustrated in the accompanying drawings, in which:

Figure 1 is a vertical transverse section through a crank case and cylinder of an internal combustion engine and showing the invention applied.

Figure 2 is a perspective of a conventional form of engine to which the invention is applied.

The invention is shown as incorporated with an internal combustion engine having a crank case 2 above which is arranged the usual combustion cylinder 3 in which operates a piston 5. The piston is connected by a link 6 to a crank shaft 7.

The invention involves a suitable upwardly extending pipe or tube 10, the head of which may be supported as by a suitable bracket clamp; the upper end of the pipe being open and covered by a suitable guard or cap 12. In the lower end of the intake pipe 10 is an inwardly opening check valve 13.

Preferably on the opposite side of the crank case from the inlet pipe 10, is an outlet pipe 14, the inner end 15 of which is arranged at the upper portion of the crank case. The upper end of the outlet pipe is supported by a clamp bracket 16 and its upper end may be covered by a pivoting elbow cap 17.

The pivoting elbow cap 17 is clearly

shown as including an elbowed cowl, and when there is a natural flow of atmospheric air, the air current will swing the cowl away from the direction from which the air current is moving, and this operates to produce a suction in the outlet pipe 14 which will act in combination with the suction produced in the crank chamber due to operation of the piston cylinders and therefore, in addition to the air taken in through the inlet valve 13 under piston pulsation, there will be an added velocity of flow through the inlet 13 due to the siphonic action produced at the end of the cowl 17.

In the operation of the engine, the pulsations of the air in the crank case, owing to the reciprocations of the pistons, serve to draw in air through the inlet valve 13, which seats to provide out flow of air. The pulsating air in the crank case is thus modified in temperature by the incoming cold air with the result that the operating parts are kept cooler with a consequent reduction in the amount of lubricating oil used and a reduction also of carbon deposit occurring from the burning of the oil residue collecting on the hot surfaces of the motor. The pulsations of the air insure the intermixing of the cool incoming air with that in the crank case and the excess air is permitted to flow out through the outlet pipe 14.

In Fig. 1 the installation is arranged as in combination with a tractor motor, in which case the outlet pipe 14 can be arranged vertically, and in Fig. 2 the outlet pipe is shown as arranged with a horizontal portion in combination with an automobile engine.

The guard or cap 12 has a wire screen 18 below the air apertures 19 and the curved section 20 of the inlet pipe is also provided with a screen 21. This curved section is preferably joined to a pipe 22 fixed to the crank case by screw threaded connections so that the wire gauze may be cleaned by the removal of the section 20.

The inlet check valve 13 is constructed with a spider 23, having a tight fit in the pipe 22, through which operates the stem 24 having the valve head 25 thereon and a spring 26, tensioned between the spider and the nut on the head of the stem. The elbow cap 17 or cowl is preferably supported on a swiveling rod 27 which is held in an open bracket 28. The skirt 29 of the cowl is slightly

separated from the top of the outlet pipe 14 so as to leave an annular space 30 through which a certain amount of air will be drawn. A gauze 31 is also inserted in the outlet pipe.

It will be noted that the air outlet in Fig. 1, with the cowl or in Fig. 2, that the air passing the outlets will cause a constant suction thereon. In Fig. 1 a certain amount of air will be drawn through the passage 30 and hence increase the ejector effect on the air outlet. The spring 26 will be of light material as the back thrust of the air would tend to seat the valve head 25, nevertheless there would be a certain resistance to the opening of the intake valve. In view of this feature it is necessary to have a suction on the outlet end, otherwise air would be drawn in through the outlet.

Various modifications and changes may be resorted to within the spirit of the invention as claimed.

What is claimed is:

1. An internal combustion engine comprising, in combination, a cylinder, a piston 25 operated therein, a crank, a connecting rod from the piston to the crank, a crank case, an air inlet pipe in the forward end of the crank case, an air outlet pipe on the opposite side of the crank case from the inlet, 30 and a cowl swivelly connected to the exhaust end of the outlet pipe, said cowl being adapted to swing in the direction of the flow of the external air in passing over the engine. 35

2. An internal combustion engine as claimed in claim 1, in which a narrow passage is provided between the cowl and the exhaust end of the outlet pipe whereby external air may flow through said passage. 40

In testimony whereof I have signed my name to this specification.

JOHN R. MILLER.
